UNITED STATES PATENT OFFICE.

CARL BAUER, OF CHICAGO, ILLINOIS, ASSIGNOR TO DOETSCH & BAUER COMPANY, OF CHICAGO, ILLINOIS, A CORPORATION OF ILLINOIS.

DESIGN FOR SETTEE FRAME OR SIMILAR ARTICLE.

Application filed January 17, 1929. Serial No. 29,656. Term of patent 3½ years.

To all whom it may concern:

Be it known that I, CARL BAUER, a citizen of the United States, residing at Chicago, in the county of Cook and State of Illinois, have invented a new, original, and ornamental Design for a Settee Frame or Similar Article, of which the following is a specification, reference being had to the accompanying drawing, forming a part thereof.

The figure is a perspective view of a settee frame or similar article showing my new design.

The ornamentation is continued throughout the lower end portions of the frame.

I claim:

The ornamental design for a settee frame or similar article as shown and described.

In witness whereof, I hereunto subscribe my name this 15th day of January, 1929.

CARL BAUER.
